UNITED STATES PATENT OFFICE

VINCENT W. RIDLEY, OF BROOKLYN, NEW YORK, ASSIGNOR TO UNITED FRUIT COMPANY, OF NEW YORK, N. Y., A CORPORATION OF NEW JERSEY

PAPER BAG

Application filed March 7, 1930. Serial No. 433,851.

This invention relates generally to improvements in the construction of and method of forming paper bags and particularly in connection with bags adapted to be used as protective wrappers for large bunches of bananas on the stalk. It has been a principal object of the invention to simplify and reduce the cost of the construction of bags of the type mentioned and at the same time to increase the strength of the same so that they will readily withstand the strains to which they may be subjected. Heretofore it has been the practice to employ, in the shipment of large bunches of bananas, bags which have the usual glued or pasted seam construction at the bottom with an opening merely cut at the center thereof to permit the end of the stalk to extend through the bottom of the bag. The opposite or open end of the bag is then usually gathered together and tied with a piece of twine or the like.

According to the present invention it is proposed to produce a bag from a tubular paper member formed with a longitudinal seam, preferably glued or otherwise cemented. The bottom of the bag will preferably, although not necessarily, be reinforced and will be closed by suitable mechanical fastening means which may be so located as to leave a large central opening of the desired size. This type of construction readily permits forming the main body of the bag in long continuous strips which are subsequently cut into sections.

With these and other objects and advantages in view, the invention will now be described by reference to the accompanying drawings which disclose several admirable embodiments and in which:

Figure 1 is a face view of the complete bag showing a corner of the same turned back to more clearly disclose its construction.

Figure 2 is a detail view showing one form of fastening and reinforcing means employed at the closed end of the bag.

Figure 3 is a view showing the closed end of the bag.

Figure 4 is a sectional view taken along the line 4—4 of Figure 1, showing on a mag-

nified scale the construction of the closed end of the bag.

Figure 5 is a similar view taken along the line 5—5 of Figure 1.

Figure 6 is a detail view showing the bottom portion of a modified form of bag.

Figure 7 is a detail view showing the bottom portion of another modified form of bag.

Figure 8 is an enlarged sectional view taken along the line 8—8 of Figure 7, and

Figure 9 is an enlarged sectional view taken along the line 9—9 of Figure 7.

Referring now to Figures 1 to 5, inclusive, which disclose one desirable form of the invention, the bag may be constructed of a sheet of paper of any suitable weight and texture formed into a tubular member 10 having a longitudinal seam 11. This seam may be glued, pasted or cemented by any suitable adhesive medium or it may be formed by the use of any desired type of mechanical fastening means. If the main body of the bag is formed of waxed or oiled paper for the purpose of excluding moisture as far as possible, it will be preferable to omit the oil or wax from the overlapping portions constituting the seam 11 in the event that some form of adhesive is to be used since a much better bond may be effected between the surfaces of the ordinary dry paper. The tubular member of which the bag is constructed may suitably be cut from a continuous strip which may be produced in any suitable way, with its side portions folded inwardly to a point indicated by the broken lines 12 in Figure 1. This will result in a four-layer construction at the edges of the strip, including the bottom layer 13, the intermediate layers 14 and 15, and the top layer 16. At the mid-portions of the bag between the fold lines 12 there will be only the two thicknesses of paper 13 and 16, which will constitute the opposite main walls of the bag.

Now, in order to partially close one end of the bag, the layers 13 and 14 of the paper on the one hand and the layers 15 and 16 on the other hand may be suitably folded around and enclose appropriate reinforcing elements. For example, the material forming the layers 13 and 14 may be folded around

85

100

a reinforcing cord or string 17 and may extend downwardly, as indicated by the portions 18 and 19 in Figure 5, to any suitable extent and may then be bent inwardly and 5 upwardly into folds 20 and 21 which terminate adjacent the cord 17. It will be understood that the showing of these features of the bag in Figures 4 and 5 is on a considerably magnified scale. The folds 18, 19, 20 10 and 21 may suitably extend downwardly less than an inch, or even half an inch. It will be understood that the layers 15 and 16 of the bag may be bent into similar folds around a cord 22. The loose ends of the cords 17 15 and 22 at the two sides of the bag may be suitably tied together to retain them in place.

Any suitable fastening means may be provided across the bottom of the bag for securing the folds in the positions indicated 20 and to close the bag to any extent desired. For example, wire staples 23 may be employed for this purpose. Where the bag is to be used to enclose a bunch of bananas, the end fastening means should be employed 25 merely toward the sides of the bag and should leave an opening 24 at the center through which the banana stalk may extend. In lieu of employing the staples 23 completely across the closed portion of the bag, a paper fastening device 25, having a large head 26 at one end and a washer 27 at its opposite end co-operating with the overturned portions of the fastener, may be employed at the two sides of the opening 24. This type of 30 fastener will provide a stronger construction adjacent the opening so that there will be less likelihood of the bag material tearing apart at these points due to rough handling. Rivets of suitable form might be employed 35 in lieu of the staples or other fastening devices or both.

In Figure 6 there is shown another form of construction. The two sides of the end of the bag are closed off in this construction by 40 means of stitching 30 employing a thread or cord of suitable weight and strength. If desired the fastening of the folds may be made more secure by the additional provision of staples 31 or similar fastening devices adjacent the sides of the central opening 32. However, the provision of these staples is not 45 essential as a bag of adequate strength may be produced by the employment of the stitching alone. Where the paper of which the bag 50 is formed is tough and durable, the reinforcement produced by the folding of the end of the bag in the manner indicated in Figures 4 and 5 may be sufficient without the introduction of extra reinforcing elements such 55 as the cords shown.

Referring now to Figures 7, 8 and 9, still another form of construction is disclosed. The tubular wall of the bag may, when flattened out, be constituted by the two layers 60 of paper 33 and 34 while the sides may be

folded inwardly as in the other forms, to provide two additional layers 35 and 36 at the edges. Now, in lieu of the rope or cord reinforcement connection with the first type 70 of bag, strips of pasteboard may be employed at the points where additional strength is required. For this purpose the wall 33 of the bag may be folded over to provide a downwardly extending portion 37 adapted to enclose a reinforcing strip 38 of tough pasteboard, leather, parchment, canvas or similar material. This strip need only be placed along the central opening in the bottom of the bag and extend sufficiently at each end to provide for securing the same to the wall and 75 folds of the bag. In a similar way the wall 34 may be folded over at 39 to enclose a suitable reinforcing strip 40. In this form of construction the portions of the folded wall surfaces 35 and 36 may be advantageously 80 folded inwardly, to provide inner folds 41 and 42, although if desired these folds may be formed outwardly by bending the material with and around the folds 37 and 39.

Any suitable means may be provided for 85 securing the folds at the bottom of the bag together. For example, staples 43 may advantageously be employed, or, if desired, the stitching shown in Figure 6 may be utilized. Where staples are employed, a pair of them 90 should be placed at opposite sides of the central opening to guard against tearing of the bag at this point; or, if desired, rivets or the fastening means provided in the first form 95 of bag may be employed. While in the drawings the staples 23, 31 and 43 have been indicated as being placed in positions parallel to the end of the bag, it will be understood 100 that these might readily be applied in a position perpendicular to the end of the bag. This would be particularly advantageous 105 adjacent the sides of the opening since a larger surface resisting a tearing action would be presented at this point.

While several forms of the invention have 110 been described in considerable detail, it is to be understood that many variations may be made in the precise constructions disclosed without departing from the spirit and scope 115 of the invention. The features which have been explained in connection with one of the embodiments may be readily applied to any other of the embodiments illustrated. It is to be further understood that the terms employed herein are used merely for purposes of 120 description and are not intended to impose any restrictions on the scope of the invention.

What I claim is:

1. A bag formed of a sheet of material having 125 its edges joined, to form a tube having a longitudinal seam, the sides of the member so formed being folded inwardly to form gussets, said member having the walls at one end doubled back upon themselves to form folds, and mechanical means for securing 130

portions of the folds together to partially close the end of the bag.

2. A bag formed of a sheet of material having its edges joined, to form a tube having a longitudinal seam, the sides of the member so formed being folded inwardly to form gussets, said member having one end doubled back to form a continuous fold, reinforcing means enclosed by said fold, and 10 mechanical means for securing portions of the fold together to partially close the end of the bag.

In testimony whereof, I have signed my name to this specification this 6th day of 15 March, 1930.

VINCENT W. RIDLEY.
